UNITED STATES PATENT OFFICE.

WILLIAM V. HAUPT, OF SHELTON, CONNECTICUT, ASSIGNOR TO ROBERT N. BASSETT COMPANY, OF SHELTON, CONNECTICUT, A CORPORATION OF CONNECTICUT.

BUCKLE.

1,163,883.

Specification of Letters Patent. Patented Jan. 18, 1916.

Continuation of application Serial No. 654,780, filed October 14, 1911. This application filed June 15, 1915.
Serial No. 34,306.

To all whom it may concern:

Be it known that I, WILLIAM V. HAUPT, a citizen of the United States, residing at Shelton, in the town of Huntington, county 5 of Fairfield, and State of Connecticut, have invented a certain new and useful Improvement in Buckles, of which the following is a specification.

My invention relates to buckles of the kind illustrated and described in my application No. 654,780, filed October 14, 1911, of which this application is a continuation, and its object is to provide a lever buckle having a back member which can be swaged 15 on running webbing. I attain this object in the preferred embodiment of my invention set forth in the following description and accompanying drawing in which like reference characters refer to corresponding 20 parts.

In the drawings: Figure 1 is a front view of one form of my buckle a part of the lever and webbing being broken away; Figs. 2 and 3, rear and longitudinal sectional views of the form shown in Fig. 1; Fig. 4, a side view of the buckle frame before the parts are assembled, and Figs. 5 and 6, rear and longitudinal sectional views of a modification.

My buckle generally comprises the frame or back A and the lever B. The back A is suitably blanked and struck up out of a sheet metal plate to form the back proper 2 having the forwardly turned side ears 3, 25 3 which latter are perforated at 4, 4. The lever B is also suitably blanked and struck up out of sheet metal to form the front portion or shield 5, the web engaging or clamping edge 6 and the laterally projecting 30 trunnions 7, 7 which latter are journaled in the perforations 4, 4 to form a pivotal connection between the lever and the back. The body portion of the back is sheared 35 transversely between the ears 3, 3, but below the pivotal connection, and is then bent forwardly forming an opening having edges 40 9 and 10 respectively which are preferably straight. A depression is thus formed in the rear face of the back above the opening 45 as shown in Fig. 4. One extremity k of the webbing C is inserted upwardly from front to rear through the opening into the depression formed in the back. The edges 50 9 and 10 are then closed on the extremity h by suitable swaging tools to permanently 55 pinch or grip the webbing between them. The webbing C having its extremity k thus securely fastened between the edges 9 and 10 is carried upwardly around the edge 9, then over the top edge of the back 2, then 60 looped downwardly and passed upwardly between the back and the lever B which latter may be shut down to lock the webbing between the edge 6 and the back 2, or to be more exact, between the edge 6 and 65 the underlying layer of webbing passing over the front of the back 2. The buckle thus strung forms an adjustable loop in the webbing which carries a cast-off or any other suitable member D. It should be 70 noticed that during the operation of closing the edges 9 and 10 on the webbing the extremity k is pocketed by the depression formed in the face of the back so that it does not interfere with the action of the 75 swaging tools. It should be further noticed that when the buckle is webbed the extremity k being seated in the depression is covered by the webbing which passes over it thereby eliminating the disadvantages in- 80 cident to an exposed end. In this form of my invention the holding of the webbing between the edges 9 and 10 is facilitated by folding it around one or more edges on the back, as for instance the edge 9 and the 85 top edge of the back which causes a binding action to be exerted thereon, thereby relieving to a considerable extent the strain on the confined extremity. When the back is sheared and depressed so that its body 90 portion forms an offset tongue it is not necessary that the tongue should always project downwardly, since it may project upwardly as shown in Figs. 5 and 6, in which the back A' is slit to form the tongue 95 12 between the edge 13 of which and the edge 14 is confined the extremity k' of the webbing. In this modification it is apparent that the buckle may be strung in various ways but is shown so that the webbing will 100 cover the back of the buckle and produce the so called rustless effect. The edges 15 of the lever B' locks the moving portion of the webbing C against the underlying layer passing over the front of the back.

It should be observed that the side ears being bent forwardly reinforce the back at the sides of the opening which latter may be

continued if desired until it extends substantially the entire width of the back as shown in Figs. 1 and 3. It should be further observed that the opening in the body 5 of the plate is always located beyond or on one side of the pivotal connection which makes its edges accessible to swaging tools when the lever is swung out of the way. The buckle may be strung in various ways, the 10 essential feature being that the extremity of the webbing shall not interfere with the action of the swaging tools when attaching the same to the buckle.

I do not claim broadly a pivoted lever 15 buckle provided with an opening having one of its sides offset so that the opening can be closed on webbing. It is to be understood, however, that the above disclosures embody 20 only the preferred forms of my invention which are susceptible to such modification as may fairly come within the scope of the appended claims.

Having now described my invention what 25 I claim and desire to protect by Letters Patent is:

1. A buckle comprising a back member 30 made out of a sheet metal plate having its body portion sheared and depressed to form an opening, the metal along one side of said opening being offset and the sides of said plate being bent up to reinforce the metal at the sides of said opening, and a web-locking 35 lever member pivotally connected to said sides and arranged to swing upwardly from in front of said opening, whereby the said plate can be engaged by swaging tools

after the back and lever members are assembled to close said opening on running webbing.

2. The combination with a running webbing, 40 of a buckle comprising a sheet metal plate having side ears turned at an angle thereto and having its body portion sheared and depressed to form an opening between said ears leaving a depression in the face 45 of said plate, and a web-locking lever pivotally connected to said ears on one side of said opening, one extremity of said webbing being passed into said depression through said opening which latter is closed 50 on the webbing to permanently attach the same to the buckle, and the said webbing being then passed over said depression to cover said extremity and between said lever and plate. 55

3. The combination with a running webbing, 60 of a buckle comprising a sheet metal plate having its body portion sheared and depressed to form an opening and its sides struck up to reinforce the metal at the sides 65 of said opening, and a web-locking lever pivotally connected to said plate on one side of said opening, the said opening being closed on said webbing to permanently attach the same to the buckle and the said webbing being then folded around one of the edges of said plate and passed between the lever and plate.

In testimony whereof I have hereunto set my hand this 27th day of May 1915.

WILLIAM V. HAUPT.
